CLAIM

The ornamental design for a compartmentalized food storage assembly, as shown and described.

DESCRIPTION

FIG. 1 is a perspective view of a compartmentalized food storage assembly showing my new design, the broken lines showing products are for illustrative purposes only and form no part of the claimed design;

FIG. 2 is a front view thereof;

FIG. 3 is a side view thereof;

FIG. 4 is a rear view thereof;

FIG. 5 is a side view thereof;

FIG. 6 is a top plan view thereof;

FIG. 7 is a bottom plan view thereof;

FIG. 8 is a perspective view thereof, in a closed position;

FIG. 9 is a front view of FIG. 8;

FIG. 10 is a side view of FIG. 8;

FIG. 11 is a rear view of FIG. 8;

FIG. 12 is a side view of FIG. 8;

FIG. 13 is a top plan view of FIG. 8;

FIG. 14 is a bottom plan view of FIG. 8;

FIG. 15 is a front perspective view of an alternate embodiment of FIG. 1; and,

FIG. 16 is a front perspective view of an alternate embodiment of FIG. 1.
